UNITED STATES PATENT OFFICE.

HERMAN KERNGOOD AND ISAAC BLUM, OF BALTIMORE, MARYLAND, ASSIGNEES TO
ALMA MANUFACTURING COMPANY OF BALTIMORE CITY, OF BALTIMORE, MARY-
LAND, A CORPORATION OF MARYLAND.

PRONG-ATTACHED SLIDING-TONGUE BUCKLE.

1,132,856.

Specification of Letters Patent. Patented Mar. 23, 1915.

Application filed November 21, 1912. Serial No. 732,690.

To all whom it may concern:

Be it known that we, HERMAN KERNGOOD and ISAAC BLUM, citizens of the United States, residing at Baltimore, in the State 5 of Maryland, have invented a certain new and useful Improvement in Prong-Attached Sliding-Tongue Buckles, of which the following is a full, clear, and exact description.

The primary object of this invention is to 10 provide a buckle, for use on knee-pants or knickerbockers, which carries its own attaching medium, so as to avoid the necessity, save the time and overcome the insecurity of sewing now commonly practised, 15 and will not readily fray or abrade the strap ends.

The invention is applicable to a variety of forms of buckles, but its most efficient application is to one having a sliding tongue.

20 The invention consists of a buckle having a cross-bar provided on opposite edges with integral prongs which are adapted to penetrate the goods and then be clenched, these prongs being arranged staggering so 25 that as they curl toward each other in the act of setting, their points will not conflict. The cross-bar is depressed nearly or quite to the plane of the back of the buckle so that it forms a sort of fulcrum upon which the 30 buckle may be tilted in order to facilitate the insertion of the strap end in the buckle.

In the accompanying drawings, illustrating the invention, in the several figures of which like parts are similarly designated, 35 Figure 1 is a top plan view; Fig. 2 is a bottom plan view, and Fig. 3 is a longitudinal section illustrating a preferred embodiment of the invention. Fig. 4 is a longitudinal section showing the buckle applied.

40 The frame has the side bars 1, with the introverted flanges 2 forming slideways for the sliding tongue; the end-bars 3 and 4, which are devoid of prongs or teeth that would penetrate the strap, and the intermediate, substantially central, cross-bar 5 which is depressed from the level of the face 45 of the frame to or substantially to the level of the back of the frame. Four, more or less, prongs 6 extend integrally from opposite edges of this cross-bar, backwardly, and they are arranged staggering so that when clenched on a garment their points will be out of line and not conflict one with another, but will curl over toward the center

of the cross-bar and alongside one another. 55 It will be understood that suitable tools or machines, having essentially a plunger or hammer and an anvil, will be used, instead of a needle and thread, to set or attach the buckle, and the comparative advantage is 60 that the work may be done more quickly, and the fastening or attachment will be more secure. The depression of the cross-bar makes of it a fulcrum upon which the buckle may be tilted in order to facilitate 65 the insertion and removal of the strap end 7. We prefer to use with this attaching feature a sliding tongue 8, mounted in the slideways formed by the introverted flanges 2, and this tongue has an opening 9 for the entrance of the free end strap 7, next to which is the gripping bar 10 having in its leading edge the upstanding dents 11 running out at an incline to nothing at about the middle 70 of the bar 10 and standing up forwardly to 75 a height sufficient to crimp the strap lengthwise and also to abut against the end bar 3 so as to restrain the tongue from escape 80 from the frame in that direction. The depressed cross-bar 5 prevents the escape of 85 the tongue in that direction, because said cross-bar overhangs the slideways in which the tongue moves. The leading edge 12 of the gripping bar 10 extends forward of the dents and underlies the end bar 3 so as to co- 90 operate with the adjacent edge of said end bar to grip the strap, especially if it be thin.

As shown in Fig. 4, the buckle is attached directly by its prongs to a garment having 90 an opening, such as the cuff of knee-pants, the parts of which are here represented at 13, and the strap end 7 is then passed up from the back of the buckle through the opening 9 and over the tongue and cross-bar 5 and thence under the end bar 4 of the frame. Strain placed on the strap will be resisted by the dents 11 and the gripping edges of the bars 10 and 3 and the strap end thus will be firmly held. The grip upon 95 the strap is further promoted by the bight 100 put in the strap by the usual finger-hold 14.

A feature of importance in connection with this buckle is that where the strap is fastened and unfastened frequently, as is 105 the case when buckles are used upon knee-pants, and any sort of penetrating buckle tongue is used, the strap is soon worn and

frayed out; but with the gripping sliding tongue this sort of damage is greatly minimized if not wholly avoided.

What we claim is:—

- 5 1. A prong-attached buckle, comprising a frame having side bars and end bars devoid of prongs or teeth, a buckle-attaching cross-bar arranged between the end bars and connecting the side bars and depressed below the level of the face of the frame and having prongs integral with and extending backwardly from its opposite edges and out of line with one another, and a strap-gripping device at one end of the 10 frame.
- 15 2. A prong-attached buckle, comprising a frame having side bars and end bars devoid of prongs or teeth, a buckle-attaching cross-bar arranged between the end bars and connecting the side bars and depressed below 20

the level of the face of the frame and having a plurality of prongs integral with and extending backwardly from its opposite edges and out of line with one another, and a strap-gripping device arranged at one end 25 of the frame and movable toward and from the cross-bar, said cross-bar when fastened to an article by its prongs serving as a fulcrum upon which the buckle may be tilted to facilitate the insertion of the free end of 30 the strap into the buckle.

In testimony whereof we have hereunto set our hands this 20th day of November A. D. 1912.

HERMAN KERNGOOD.
ISAAC BLUM.
